[57] **CLAIM**

The ornamental design for the knife handle with blade guard, as shown and described.

DESCRIPTION

FIG. 1 is a perspective view of a knife handle with blade guard showing our new design with the blade guard in an extended position;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a perspective view of a knife handle with blade guard showing our new design with the blade guard in a retracted position;

FIG. 9 is a top plan view thereof;

FIG. 10 is a bottom plan view thereof;

FIG. 11 is a left side elevational view thereof;

FIG. 12 is a right side elevational view thereof;

FIG. 13 is a front elevational view thereof; and,

FIG. 14 is a rear elevational view thereof.

The broken line showing of the blade and pivot is for illustrative purposes only and forms no part of the claimed design.
